CLAIM

The ornamental design for a round ultra-thin panel light, as shown and described.

DESCRIPTION

FIG. 1 is a perspective view of a round ultra-thin panel light showing my new design;

FIG. 2 is a left side elevation view thereof;

FIG. 3 is a rear elevation view thereof;

FIG. 4 is a front elevation view thereof;

FIG. 5 is a right side elevation view thereof;

FIG. 6 is a top plan view thereof;

FIG. 7 is a bottom plan view thereof;

FIG. 8 is a bottom side perspective view thereof; and,

FIG. 9 is a perspective view thereof, shown in divided state. The broken lines in the drawings depict portions of the round ultra-thin panel light that form no part of the claimed design.
